UNITED STATES PATENT OFFICE.

DANIEL W. SHIEK, OF LETTSVILLE, IOWA, ASSIGNOR OF TWO-THIRDS TO
C. O. COLE, OF SAME PLACE, AND E. G. GROSJEAN, OF MOUNT EATON,
OHIO.

MECHANICAL AUTOMATIC SELLING-MACHINE.

SPECIFICATION forming part of Letters Patent No. 329,225, dated October 27, 1885.

Application filed June 23, 1884. Serial No. 135,809. (No model.)

To all whom it may concern:

Be it known that I, DANIEL W. SHIEK, of Lettsville, in the county of Louisa and State of Iowa, have invented certain new and 5 useful Improvements in Mechanical Automatic Selling-Machines; and I do hereby declare the following to be a full, clear, and exact description of the invention, such as will enable others skilled in the art to which it pertains 10 to make and use it, reference being had to the accompanying drawings, which form part of this specification.

My invention relates to an improvement in mechanical automatic selling-machines for cigars and other articles; and it consists in the combination of the drawer or slide having attached to its rear edge a smooth rod, a clamping device through which the smooth rod passes, and which is provided with an arm for 15 catching upon the top of the coin and preventing the clamping device from operating, a pivoted U-shaped rod having hooks upon its front end, and which serve to catch the coin at its lower end, and the passage-way 20 through which the coin passes, as will be more fully described hereinafter.

The object of my invention is to provide an automatic selling-machine in which, when a coin of the required denomination is dropped, 25 the drawer or slide can be drawn open and the article taken out, but which drawer or slide cannot be opened unless a coin of the exact denomination is used, and thus enable persons to wait upon themselves at the stores without having to call upon the store-keeper to wait 30 upon them.

Figure 1 is a vertical longitudinal section of a machine embodying my invention. Fig. 40 2 is a plan view showing the drawer, the smooth rod, and the frictional clamping device. Fig. 3 is a plan view of the same with the drawer removed. Fig. 4 is a perspective of the bent U-shaped lever.

A represents a show-case having the inclined board or bottom B, and upon which the cigar-box is placed. The end is removed from this cigar-box, so that the cigars will slide from the box C upon the lower edge of

the inclined board B, and rest upon the top of the drawer or slide D. Through this slide 50 or drawer D is made the slot E, into which one, and only one, of the cigars will fall. Even if the cigars should run down the board B so as to fill the whole front of the showcase above the top of the slide or drawer D, 55 only one cigar will drop through the slot or opening made to receive it. The bottom of this slot is formed by a thin plate of sheet metal or other material, F, through which are made a suitable number of slots, G. Secured 60 to the center of the back edge of this drawer or slide D is the smooth rod H, which is provided with the stop I at its rear end, both for the purpose of preventing the drawer from being drawn too far out and for the purpose of 65 operating the bent lever J, which is pivoted upon the top of the board or support L. Just inside of this board or support L is placed the frictional clamping device N, which consists of a rod having an opening through its upper 70 end for the rod H to pass through, and which has its lower end loosely held by the bracket O, secured to the lower edge of the support L. This frictional clamping device N has its upper end to move freely back and forth in a 75 line with the movement of the rod H, and it is operated entirely by its frictional contact with the rod.

When the drawer is pushed back into position after having been thrown out, the frictional contact of the rod H against the device N pushes the upper end of the device back until it rests against the support L, when the rod H passes freely through without any hindrance on the part of the device N. When, 80 however, it is attempted to pull the drawer outward, the frictional contact of the device N upon the rod H causes the upper end of this device N to be drawn forward just far enough to cause the device N to clamp the rod tightly, 85 and thus prevent the drawer or slide D from being drawn outward. When the drawer or slide is to be drawn outward, the upper end of the clamping device N must be held in such a manner that it cannot follow the movement of the 90 rod H, so as to be inclined forward. This for-

ward movement of the upper end of the clamping device N is prevented both by a coin of the required denomination, which is dropped into the drawer to pay for the cigar or other article, and by the curved lever J. Should the proprietor at any time wish to allow the slide to be drawn outward, it is only necessary for him to move the rear end of the pivoted lever J to one side, so that its front end will catch over the front edge of the clamping device N, so as to prevent it from moving forward, and then the drawer or slide D can be drawn freely outward. This lever J is shaped, as shown, so as to be automatically operated by the stop I in the rear end of the rod H. When the drawer or slide D is drawn outward, the stop I strikes against the rear end of this lever just before the rod completes its movement, and the rear end of the lever is pushed to one side, so that its front end is made to catch over the front side of the clamping device N. This lever, while catching against the front edge of the clamping device, prevents the clamping device from engaging with the rod H after the coin is dropped and before the drawer or slide has had time to complete its full movement. Were it not for this lever, when the coin drops into the drawer, the outward movement of the drawer would be checked before it would have been moved far enough to allow the cigar or other article to be taken out of the slot E.

Secured to the front side of this clamping device N is the bent arm P, which projects forward inside of the rear end of the bent rod Q, and which arm is intended to strike upon the top of the coin of the proper denomination, which has been dropped in through the slide or passage-way R, extending from the opening in the front of the upper edge of the slide or drawer D; and which extends down along the top of the inclined board or bottom piece S. This passage-way is preferably covered over, and it may be curved in any suitable manner, so as to prevent strips of pasteboard and other similar material from being dropped into the passage-way for the purpose of catching under the arm P. If a coin of the proper denomination is dropped through the passage-way R, it passes down until it strikes against the lower part of the bent rod Q, which is cut away slightly at its bottom edge, as shown at V, so as to allow the lower edge of the coin to project through. This coin prevents the upper end of the clamping device N from moving forward by frictional contact with the rod H, because the end of the rod or arm P bears upon the top of the coin and prevents any movement of the arm, and through the arm the upper end of the clamping device. If a coin of a smaller denomination than the required price for the article to be sold is dropped in through the passage-way R, it slides down through the opening V, made in the bottom of the bent rod Q, and on down into the drawer 65 without operating the machine in any way. Coins of a larger denomination cannot be

dropped in, because the mouth of the passage-way R is not made wide enough.

The bent U-shaped rod Q is pivoted upon the top of the inclined board or support S, 70 and has its two front ends made hook-shaped, as shown, and which project up through suitable slots in the bottom of the drawer or slide D. These hook-shaped ends U serve to catch against the outer side of the cigar as 75 the drawer or slide D is being drawn outward, and which hook-shaped ends U give before the forward movement of the cigar and sink downward, so as to allow the drawer or slide D to be pulled outward. As these ends U sink 80 downward, the rear or lower end of the rod Q is raised upward, so as to release the coin and let it drop down into the drawer. In case no cigar should drop into the slot from any cause whatever, the upper ends of the rod U will 85 not be operated by the outward movement of the drawer or slide D, and hence the coin is simply held in the opening V, and the drawer can be pushed freely in and out at will. If the cigars have stuck together above the slot 90 E, so that one cannot fall down into the slot, they may be loosened by forcibly pushing the drawer back and forth. Should one drop into the slot the next time the drawer is pulled out, the front hook-shaped ends of the bent rod Q 95 are depressed, the coin released, and then the clamping device N is again free to operate, and thus prevent the drawer or slide from being pulled out. Thus it will be seen that a 100 cigar must be drawn out with the drawer or the coin is simply held without being dropped into the drawer. The coin while resting upon the inclined board S covers the recess T, which is made in the board, and into which the lower end of the arm P would drop if the coin were 105 not there. As the arm P strikes against the top of the coin, the automatic clamping device 110 N cannot move forward at its upper end.

My invention is here shown in connection with a cigar-seller only; but it is evident that 115 the same principle may be employed to many different articles, the size of the slot E being varied according to the article being sold. As the price of the article varies, so the passage-way R and the opening V through the lower 120 end of the U-shaped rod Q will be varied accordingly, to correspond to coins of different denominations.

Having thus described my invention, I 125 claim—

1. The combination of the slide or drawer provided with a suitable opening to receive the article being sold, a frictional rod which projects from the rear end of the slide, an automatically-acting clamping device through 130 which the rod passes, and a rod connected to and operated by the clamping device for catching upon the coin, substantially as shown.

2. The combination of the slide or drawer provided with a slot or opening and having a 135 rod projecting from its rear side, the automatic clamping device through which the rod

passes, and which is provided with an arm, the U-shaped rod Q, provided with hooks at its upper end and with an opening at its lower end to receive the coin, substantially as described.

5 3. The combination of the drawer or slide provided with a slot, E, smooth rod H, clamping device N, provided with the arm P, the U-shaped rod Q, having hooks at its upper end to be operated by the cigar or other article in

the slot, and the opening V at its lower end to hold the coin, the inclined board S, and the passage-way, substantially as set forth.

In testimony whereof I affix my signature in presence of two witnesses.

DANIEL W. SHIEK.
